[57] CLAIM

The ornamental design for a supplied air fan and electronics unit for a personal environment system including an air mixing extension unit, as shown.

DESCRIPTION

FIG. 1 is a left front perspective view of a supplied air fan and electronics unit for a personal environment system including an air mixing extension unit showing our new design;

FIG. 2 is a top view of the supplied air fan and electronics unit for a personal environment system of FIG. 1;

FIG. 3 is a front elevational view of the supplied air fan and electronics unit for a personal environment system of FIG. 1;

FIG. 4 is a right side elevational view of the supplied air fan and electronics unit for a personal environment system of FIG. 1;

FIG. 5 is a left side elevational view of the supplied air fan and electronics unit for a personal environment system of FIG. 1; and,

FIG. 6 is a bottom view of the supplied air fan and electronics unit for a personal environment system of FIG. 1.
